ALARM CIRCUIT

Roger W. McBrien, Alton, and Norval F. Wilson,
East Alton, Ill.; said Wilson assignor to said
McBrien

Application December 28, 1931, Serial No. 583,434

2 Claims. (Cl. 177—356)

Our invention has relation to improvements in electric alarm circuits and it consists in the novel features of construction more fully set forth in the specification and pointed out in the claims.

5 The present invention is an improvement over that shown in our pending application, Serial No. 552,904, filed July 24, 1931, and, like that, is particularly directed to an alarm circuit which may be connected to various power circuits in 10 buildings and residences primarily for sounding, or otherwise giving an alarm in case of fire, and secondarily for permanently opening a circuit that has been shorted.

The objects of the present invention are to 15 simplify and make more certain of operation the circuit described in the above mentioned application, which we accomplish by providing a two-step electromagnetically operated switch between the power circuit and an oscillating two 20 circuit control switch, said two-step switch serving to close either the alarm circuit in case of fire, or to open the power circuit in case of a permanent short therein. The manner in which this object is accomplished, together with the 25 advantages inherent in our improved device, will be better apparent from a detailed description of the invention in connection with the accompanying drawing, in which:

Figure 1 is a diagrammatic view of our improved alarm circuit applied to two power circuits connected in parallel; Fig. 2 is a front elevation of the box and apparatus mounted therein for the respective power circuits in the building that is to be protected by the device, the cover 30 of the box being removed; and Fig. 3 is a vertical cross-section through the relay box taken on the line 3—3 of Fig. 2.

Referring to the drawing, the power circuits comprise conductors 1, 2 and 1', 2', conductors 40 1, 1' being directly connected to line wire L, and conductors 2, 2' being connected to fuses 6, 6' by conductors 3, 3'. Conductors 4, 4' connect the fuses 6, 6' to line wire L'. The ends of fuses 6, 6' connected to conductors 3, 3' are also 45 connected by conductors 8, 8' to the pivots 5, 5', on which are mounted similar double contact switches 7, 7'. Spring contacts 9, 9' are mounted adjacent to the ends of switches 7, 7' and said switches are normally held out of contact with 50 said contacts by triggers 10, 10', which comprise armatures within coils 11, 11'. It will be observed that in the drawing the switch 7 is shown in its normal position while the switch 7' is 55 shown after it has been released to engage contact 9'. Corresponding ends of coils 11, 11' are

connected to line wire L' by conductors 12, 12' respectively, while the opposite corresponding ends of said coils are connected to armatures 10, 10' respectively.

The switches 7, 7' and associated parts just described constitute relays for effecting a connection between their respective power circuits and the alarm circuit should a fire or a short circuit occur in one of the power circuits, as will be more apparent hereinafter.

Our alarm circuit is primarily intended to give an alarm in case of a fire, consequently, thermostatic switches of any common type are distributed throughout the building that is protected by our invention. Each thermostatic switch 13 is 15 connected in series with a flasher, or blinker (which may be termed a thermo-electric flasher), comprising contacts 14 and 15, and a coil of nichrome wire 16 which is designed, on being heated by a flow of current, to separate the contacts, thus interrupting the flow of current. As the coil cools, the contacts again come together, producing a continuously interrupted flow of current across the conductors of the circuit.

The foregoing description shows that fuses 6 25 and 6' and coils 11 and 11' are in parallel-series connection with the power circuit and that when these circuits are operating under load, current will flow through the fuses 6 and 6'. However, when either of the thermostatic switches 13 is 30 closed there will be a heavy current flow through either fuse 6 or 6' because the flasher coil 16 is of low resistance and the fuses 6 and 6', depending on which switch 13 is closed, will be blown and cause the current to flow through either coil 35 11 or 11'.

Assuming that thermostatic switch 13 in the power circuit comprising conductors 1', 2' closes, the coil 11' will be energized and will withdraw the trigger 10' from the switch 7', allowing said switch 40 to be closed (under the influence of a spring hereinafter referred to and shown in Fig. 3) on the contact 9' (as shown in Fig. 1). The energizing of the coil 11' is but instantaneous since the circuit through the coil is opened immediately that the switch 7' breaks contact with the trigger 10'. Therefore, the trigger 10' immediately resumes its original position (under the influence of a spring) so as to be in the path of contact 30' which impinges on said trigger.

At this point it should be pointed out that a transformer T has its primary winding connected across the line by means of conductors 18 and 19 leading to one end of said winding and conductor 20 leading from the other end of the wind-

ing to a trigger armature 21 normally operating to hold the switch 22 out of engagement with a contact 23, the pivot end of switch 22 being connected to line wire L' by a conductor 24. Thus, the transformer primary winding is connected in series with the 110 volt line. The secondary winding of the transformer T is connected to the primary winding by a conductor 25 and at the opposite end to a coil 27 by a conductor 26, the opposite end of said coil being connected to the spring contacts 9, 9' by a conductor 28. The connection of the secondary winding to the primary winding is a matter of convenience as said connection might just as well be made to the wire 18. It is thus apparent that the circuit of the transformer secondary is closed when either of the switch levers 7, 7' engage contact 9 or 9'. The transformer secondary circuit closed by the action of switch 7' may be traced as follows:

From one end of the transformer secondary through conductor 26, coil 27, conductor 29, to contact 9', switch lever 7', conductor 8', conductor 3', conductor 2', through the closed switch 13 and flasher (elements 14, 15 and 16), to conductor 1' and line wire L, conductor 18, conductor 19, conductor 25 and transformer secondary whatever current may leak through the load across conductors 1', 2' is negligible and will not affect the action of the coil 27. The actuation of the switch lever 7' breaks the connection between the power circuit and the line and connects the transformer secondary in series with the power circuit. This results in the flow of a low voltage current from the transformer secondary through the coil 27 and the flasher (elements 14, 15 and 16) causing current to intermittently pass through the coil 27 and intermittently attract armature 32 depending from float 33 within

The casing 34 and its associated parts about to be described comprise an oscillating control switch for closing either the alarm circuit, or the safety circuit about to be described. The casing 45 34 has a well 35 depending from it normally filled with mercury to the level indicated by x in the diagram and a partition 36 divides the casing into two compartments 37 and 38. There is a small port 38' at the bottom of the partition 36. Compartment 37 houses the float 33 with its 50 depending armature 32 extending into the well 35 and compartment 38 has contacts 39 and 40 extending into it, the latter being somewhat longer, and, of course, closer to the level of the mercury when the actuating coil 27 is de-energized. There is also a contact 41 extending into the bottom of the well 35 and making permanent electric connection with the mercury. The intermittent flow of low voltage current through the coil 27 causes the float 33 to bob up and down, or oscillate in the mercury, displacing some of the mercury which splashes over the partition 36 into compartment 38, raising the level therein until the mercury touches contact 40. When this contact is made between the mercury and the contact 40, the oscillating control switch circuit which closes the alarm circuit is activated.

This oscillating control switch circuit is as follows: from conductor 18 to contact 41 through the mercury in casing 34 to contact 40, through conductor 42 to the thermo-electric element 43, through conductor 44 to coil 45 associated with armature 21, through said armature and switch 22 to conductor 24 and line wire L'. The thermo-electric switch comprises a high resistance coil

46 and a pair of contacts 47, 47 in parallel therewith and adapted to be closed by the warping action produced when the coil 46 becomes sufficiently heated. The coil 46 is of sufficiently high resistance so there will not be enough current flowing through coil 45 to attract armature 21 until the contacts 47, 47 have been brought together. It will take approximately 40 seconds for the coil 46 to become sufficiently heated to close the gap between contacts 47, 47 and allow 10 sufficient current to flow through the coil 45 to attract the same and release the switch lever 22 so that it may close against the contact 23. On account of this time element the switch 22 cannot be closed on the contact 23 as the result of 15 a short in the power circuit. This circuit just traced may be termed the alarm relay circuit as it operates the relay comprising elements 21, 22, 23 and 45 to close the alarm circuit which comprises line wire L', conductor 24, switch lever 22, 20 contact 23, conductor 24', alarm conductor 18 and line wire L. Obviously, the release of switch lever 22 opens the transformer primary circuit. Thus, it is apparent that if any of the thermostatic switches 13 are closed and remain closed 25 for an appreciable length of time, the alarm relay is actuated to close the alarm circuit, producing the alarm at the fire department, or in other suitable places.

Some provision must be made for preventing 30 the alarm circuit from being actuated, by a short in any of the power circuits. We, therefore, are embodying in the invention a safety circuit, by means of which the power circuit, impaired by a permanent short, will be immediately opened 35 so that no damage may result to any apparatus that may be the cause of the short. We will assume that conductors 1 and 2 are shorted so as to cut out the resistance of the load on this circuit. This will cause a current flow, just as in 40 the case above described, when the switch 13 is closed, which causes the fuse 6 to blow and then actuates switch 7. However, the flow of current through the coil 27 instead of being intermittent, as in the case of fire, will now be 45 steady and the float 33 will be drawn downwardly into the mercury in casing 34 and held down so as to cause the displaced mercury to contact with the terminal 39, which is connected to a high resistance coil 49 of a second thermal switch 50 similar to switch 43. The coil 49 is also connected to contacts 30, 30' by the conductor 31 so that the flow of current at the line voltage will flow through the coil 49, it being remembered that contact 30 is in engagement with trigger 10. 55 When the coil 49 has been sufficiently heated contacts 51, 52 will be warped together and provide a shunt path for the current around the coil 49, resulting in an increased current flow through the coil 11 which becomes energized, and 60 withdraws the trigger 10 from switch contact 30, thus opening the circuit at this point, and at the same time opening the circuit of coil 27 at 9. The power circuit 1, 2 is now completely out of commission as it is disconnected from the line. 65 It will be noted that the gap between contacts 51, 52 is less than between the contacts 47, 47 so that the safety circuit above defined will close before the alarm circuit is closed.

It is apparent that even though switch 7, or 7', 70 has been actuated by the closing of switch 13 (due to fire) it is still in condition to respond to the effects of a permanent short circuit in order that the circuit may be opened so that the alarm circuit may respond to effects in other circuits 75

before any damage results. Thus, a short in one of the power circuits does not interfere with the operation of our improved alarm circuit in connection with another power circuit, but merely results in the particular power circuit having the short being temporarily disconnected from service.

As heretofore shown a fire in the vicinity of the thermostatic switches 13, so that they will be under the influence of abnormal heat, will cause the switches to close and produce an uninterrupted current flow through the coil 27 oscillating the control switch comprising the casting 24 and associated parts. This as we have seen causes the alarm to sound.

A short in the circuit brings into operation the safety circuit through the closing of switch contacts 51, 52 by the overheating of coil 48 and the downward pull on the control switch. However, in the case of an overload the current flow is not as great as when there is a short, owing to the resistance in the circuit, and is insufficient to heat the coil 48 to a degree necessary to bring contacts 51, 52 together and operate the control switch.

The construction of the mechanism in the relay box B may be described as follows:

A pair of fibre supporting elements 60, 60 are mounted in the box B in spaced relation for the purpose of supporting the switches 7, 7' and associated mechanism. Since the switches and their associated parts are identical but one will be described. Each element 60 is U-shaped, having an upper leg 61 and a lower leg 62, below which in spaced relation is disposed a fibre block 63. An insulating panel 64 extends from top to bottom of the box B and is secured to the members 61, 62 and block 63. Mounted between the back of the member 60 and the panel 64, about midway between arms 61 and 62, is a metallic block 65, on which is pivotally mounted switch lever 1 (and of course 1'). The switch lever comprises two flat sections 66, 66 separated intermediate their ends to provide space for receiving the metallic block 65, and also the spring socket 67 of a reciprocable contact member 68. The reciprocating member 68 also includes a pin 69 which is disposed within socket member 67 and fixed to it, and the pin is slidably mounted in plate 70 secured to member 60 and a bushing 71 is fixed in opening 72 in panel 64. A coiled spring 73 is disposed over the pin 69 and seated in the socket 67, said spring operating to press the contact member outwardly through the panel 64. A socket 74 is secured to the outside of panel 64 concentric with bushing 71 and has an opening 75 through the bottom to permit the pin 69 to pass therethrough, and a fuse plug 76 (carrying the fuse 6) is adapted to be screwed into the socket 74 and have its center contact engage pin 69. As the plug 76 is screwed into the socket 74 the pin 69 is pressed inwardly until the inner end of pin 69 engages contact 77 mounted at the back of member 60. In order that an improvised contact may not readily be made from the socket 74 to the pin 69 a fibre bushing 78 is inserted in the bottom of the socket 74.

Each switch lever 7, 7' has its contact 30, 30' secured to it in spaced relation by means of fibre brackets 79, 79 and a spring 80 secured to panel 64 and lever 7 or 7' exerts tension on the lever so as to urge the lower lever arm toward the panel 64 and the upper lever arm toward the contact 9, or 9' secured by means of a screw s to the member 61. Each screw s also passes through

a metallic bracket 81 which assists in fastening panel 64 to the member 61. There is also a metallic bracket 82 secured to member 60 in the back of box B and a connecting bracket 83 is fastened to brackets 81, 82. The brackets 83 of the respective switch units in box B are connected by a bus-bar 84.

Coil 11 is mounted between members 62 and 63 and is provided with a movable core, or armature, 10, said armature being urged upwardly by 10 a spring 85 seated in socket 86 within the coil. There are also brackets 87, 88 opposite the bottom of the panel 14, said brackets being connected by a bracket 89. Brackets 89, 89 of each unit are also connected by bus-bar 90.

It will be observed that the socket member 67 is provided with an annular flange 67' which flange is adapted to engage the members 66, 66 of lever 1 after the lever 1 has been actuated by the release of trigger armature 10. As above pointed out, the spring 80 actuates the lever 1 when the armature 10 releases it and it is oscillated to a position where it is inclined just about oppositely to its inclination as shown in Fig. 3. In order to again place the lever 1 in operative position it must be reset or oscillated back to the position shown in Fig. 3, which is done by the removal of the plug 76 which allows the spring 13 to reciprocate the contact member 68 through the panel 64, carrying the lever 1 with it by virtue of the engagement of the annular flange 67' with the lever members 66, 66. The fuse plug, as explained above, has previously been destroyed, therefore the mere act of removing the destroyed plug for the purpose of inserting a new one restores the lever 1 to its operative position.

A box 91 is provided for housing the switch 34, switch 22 and associated parts. There is also a resetting stem 92 mounted in one side wall of said box for resetting the switch 22 after the same has been released to close the alarm circuit. By pushing the stem 92 inwardly over the tension of spring 93 the switch is moved to overcome the tension of spring 94 until it is again bearing against armature 21.

Having described my invention, I claim:

1. A combined power and alarm system comprising a power circuit connected to a source of power and including a fuse in series therewith, a two-step electromagnetically operated device 50 having a stepping magnet for controlling the stepping thereof normally connected in shunt to said fuse, a normally open alarm switch, an intermittent interrupter having interrupting contacts and control means therefor, a connection 55 across the power circuit including in series the alarm switch, the interrupter contacts and the interrupter control means, the capacity of the fuse being such that upon the occurrence of a short across the power circuit or upon the closure 60 of the alarm switch the fuse will blow, thereby diverting current to the stepping magnet and cause the stepping magnet to step the two-step device one step, switching means operated by the first step of the device for opening the first magnet 65 circuit by disconnecting the power source from the power circuit and preparing a second circuit therefor, means for differentiating between the intermittent closure of the power circuit by the intermittent interrupter and a permanent short 70 across the power circuit including means for closing a first circuit in response to the operation of the intermittent means and this circuit and a second circuit in response to a permanent short 75 and for closing the first circuit a predetermined

- time after closure of the second circuit, means also operated on the first step of the device for associating the power circuit with the differentiating means, means operated by the closure of the 5 first differentiating circuit for controlling an alarm circuit and means controlled by the closure of the second differentiating circuit for completing the second stepping magnet circuit and means controlled by the second step of the device for disassociating the differentiating means from the power circuit to thereby prevent further response of the differentiating means to the power circuit.
2. A combined power and alarm system comprising a power circuit connected to a source of power and including a fuse in series therewith, a two-step electromagnetically operated device having a stepping magnet for controlling the stepping thereof normally connected in shunt 10 to said fuse, a normally open alarm switch, an intermittent interrupter having interrupting contacts and control means therefor, a connection across the power circuit including in series the alarm switch, the interrupter contacts and the interrupter control means, the capacity of the 15 fuse being such that upon the occurrence of a short across the power circuit or upon the closure of the alarm switch the fuse will blow, thereby diverting current to the stepping magnet and cause the stepping magnet to step the two-step device one step, switching means operated by the first step of the device for opening the first magnet circuit by disconnecting the power source from the power circuit and preparing a second circuit therefor, means for differentiating between the intermittent closure of the power circuit by the 20 intermittent interrupter and a permanent short across the power circuit, means also operated on the first step of the device for associating the power circuit with the differentiating means, means operated by the differentiating means in response to the intermittent closure of the power circuit for controlling an alarm circuit and means operated by the differentiating means in response to a permanent short for completing the second 25 stepping magnet circuit and means controlled by the second step of the device for disassociating the differentiating means from the power circuit to thereby prevent further response of the differentiating means to the power circuit.

ROGER W. McBRIEN. 25
NORVAL F. WILSON.
